UNITED STATES PATENT OFFICE.

EDWIN H. STEEDMAN, OF ST. LOUIS, MISSOURI.

TONGUE-SWITCH.

1,090,822.

Specification of Letters Patent. Patented Mar. 17, 1914.

Application filed January 17, 1914. Serial No. 812,648.

To all whom it may concern:

Be it known that I, EDWIN H. STEEDMAN, a citizen of the United States, residing at St. Louis, Missouri, have invented a certain new and useful Improvement in Tongue-Switches, of which the following is a full, clear, and exact description, such as will enable others skilled in the art to which it appertains to make and use the same.

This invention relates to tongue switches of the type described in my prior Patent No. 1,049,936, dated January 7, 1913.

One object of my present invention is to provide a tongue switch which is more efficient than the switch shown in said patent in restraining lateral forces that tend to move the tongue crosswise of the body part of the switch and in supporting vertical forces acting at the heel end of the tongue which tend to tilt the tongue vertically. And another object is to provide a design of switch of the type above-mentioned that is particularly adapted for long-radius switches, namely, switches in which the wheel flange grooves in the body part lie comparatively close together at the heel end of the tongue. To this end I have provided the body part of the switch with a floor for the tongue which is so designed that it is possible to make the semi-cylindrical-shaped pivotal portion at the heel end of the tongue tapered and of greater diameter than the corresponding part of the switch described in my prior patent above-referred to, thereby enabling the switch to more effectively restrain lateral forces which tend to move the tongue crosswise of the body part and support vertical forces at the heel end of the tongue which tend to tilt the tongue vertically. Said floor is provided with a rear portion that lies in a lower horizontal plane than the front portion of the floor on which the main portion of the tongue rests. Consequently, it is possible to make the semi-cylindrical-shaped pivotal portion on the tongue of a long-radius switch of the same diameter as the corresponding portion of a short-radius switch without having the pocket for said pivotal portion cut into or intersect the wheel flange grooves in the body part of the switch.

Figure 1 of the drawings is a top plan view of a tongue switch constructed in accordance with my invention; Fig. 2 is an enlarged top plan view of a portion of said switch; Fig. 3 is a longitudinal sectional

view taken through the center of the switch, the tongue being shown in elevation and the body part of the switch in section; and Fig. 4 is a transverse sectional view taken on the line 4—4 of Fig. 3.

Referring to the drawings which illustrate the preferred form of my invention, A designates the body part of the switch, and B designates the oscillating tongue that is mounted on said body part, both of said members being preferably cast from manganese steel or some other suitable hard steel. The body part A is provided with a horizontally-disposed floor on which the tongue B rests, and in the preferred form of my invention as herein shown, said floor comprises two portions that are located in different horizontal planes. The front portion 1 of said floor forms a supporting surface for the main portion of the tongue B, and the rear portion 2 of said floor which is located in a lower horizontal plane than the front portion 1, as shown in Fig. 3, forms a supporting surface for the semi-conical-shaped pivotal portion 3 at the heel end of the tongue. The body part A of the switch has a pocket that conforms to the shape of the semi-cylindrical-shaped pivotal portion 3 at the heel end of the tongue, and said pocket projects laterally underneath the wheel flange grooves 4 formed in the top face or wheel-tread surface of said body part, as shown in Fig. 4. By constructing the body part of the switch in this manner, namely, providing it with a tongue-supporting floor which comprises a rear portion that is located in a lower horizontal portion than the front portion, I am able to make the semi-cylindrical-shaped portion 3 at the heel end of the tongue deeper and of greater diameter than the semi-cylindrical-shaped pivotal portion on the tongue of the switch shown in my prior patent previously referred to. Consequently, the switch herein shown is more efficient than the switch shown in my said prior patent in restraining lateral forces which tend to move the tongue B crosswise of the body part A, and in supporting vertical forces acting at the heel end of the tongue which tend to tilt the tongue vertically. In other words, the horizontally-disposed bearing surface 2 of the body part on which the heel end of the tongue rests, is so large that there is little tendency for the tongue to wear and thus rock vertically owing to the fact that the

vertical forces acting at the heel end of the tongue are distributed over an exceptionally large area and the overhanging walls of the pocket in the body part which 5 embrace the semi-conical-shaped portion 3 at the heel end of the tongue and hold the tongue firmly down on the rear portion 2 of the floor of the body part, have such an exceptionally large bearing area on the tongue 10 that it effectively restrains lateral forces which tend to move the tongue crosswise of the body part. Moreover, such a design makes it possible to build a long-radius switch in which the semi-cylindrical-shaped 15 pivotal portion of the tongue is the same diameter as the corresponding part of a short-radius switch, owing to the fact that the rear portion of the floor in the body part is dropped far enough so that the pocket for 20 said pivotal portion will not cut into or intersect the wheel flange grooves in the body part of the switch.

The means for retaining the tongue in operative position in the body part is preferably the same as the means used for this 25 purpose in the switch shown in my prior patent previously referred to, and comprises a bearing member of quarter-box 5 that embraces a conical surface on the front side of 30 a depending lug 6 on the tongue and a wedge-shaped locking device 7 for holding said bearing member in engagement with said lug and causing it to exert rearward and downward pressure on said lug and tongue.

Having thus described my invention, what 35 I claim as new and desire to secure by Letters Patent is:

1. A tongue switch comprising a body part having wheel flange grooves and provided with a floor whose rear portion is 40 located in a lower horizontal plane than the front portion of the floor, and a tongue provided at its heel end with a curved piv-

otal portion whose lower end rests on the rear portion of the floor of the body part, 45 the lower end of said pivotal portion being wider than the horizontal distance between the inner edges of the wheel flange grooves in the body part of the switch.

2. A tongue switch comprising a body 50 part having wheel flange grooves and provided with an undercut pocket whose bottom is flat and extends laterally underneath the portion in which said grooves are formed, a horizontal supporting surface arranged in advance of said pocket in a higher horizontal plane than the bottom of the pocket, a movable tongue resting on said supporting surface, and a depending pivotal portion at the heel end of the tongue 60 conforming to the shape of said pocket and provided with a flat lower end that rests upon the floor of the pocket.

3. A tongue switch comprising a body 65 part provided with wheel flange grooves, a floor on said body part made up of a front portion and a flat rear portion which is located in a lower horizontal plane than said front portion and extends laterally underneath the portions of said 70 body part in which said wheel flange grooves are formed, a movable tongue resting on the front portion of said floor, and a tapered pivotal portion at the heel end of the tongue fitting in an undercut pocket 75 in said body part and having its lower end projecting downwardly below the tongue proper and resting upon the flat rear portion of said floor.

In testimony whereof I hereunto affix my 80 signature in the presence of two witnesses, this 12th day of January 1914.

EDWIN H. STEEDMAN.

Witnesses:

GEORGE R. LADSON,
EDWIN S. HARRISON.

It is hereby certified that in Letters Patent No. 1,090,822, granted March 17, 1914, upon the application of Edwin H. Steedman, of St. Louis, Missouri, for an improvement in "Tongue-Switches," an error appears in the printed specification requiring correction as follows: Page 2, line 28, for the word "of" read *or*; and that the said Letters Patent should be read with this correction therein that the same may conform to the record of the case in the Patent Office.

Signed and sealed this 21st day of April, A. D., 1914.

[SEAL.]

J. T. NEWTON,
Acting Commissioner of Patents.
